UNITED STATES PATENT OFFICE.

PHILIP MEDART, OF ST. LOUIS, MISSOURI, ASSIGNOR OF ONE-HALF TO
WILLIAM MEDART, OF ST. LOUIS, MISSOURI.

FRICITION-CLUTCH.

No. 833,537.

Specification of Letters Patent.

Patented Oct. 16, 1906.

Application filed March 29, 1906. Serial No. 308,713.

To all whom it may concern:

Be it known that I, PHILIP MEDART, a citizen of the United States, residing in the city of St. Louis, in the State of Missouri, have invented certain new and useful Improvements 5 in Friction-Clutches, of which the following is a specification.

My invention relates to friction-clutches of the class in which divided rings or segments 10 are adapted to engage the rim of a pulley or other part to be driven and are expanded and contracted by link connections between the ends of the segments, which are operated by connections with a sleeve or ring shifted 15 by a lever or other operating device. A friction-clutch of this class is shown in my United States Patent No. 788,726, of May 2, 1905.

The object of my present invention is to 20 improve clutches of this class in such manner as to make them more simple, compact, and cheap in construction, more easily adjusted, and more secure and reliable in operation.

My invention may be embodied in a clutch 25 adapted to connect a band-pulley to a continuously-running line-shaft or in a friction-coupling in which the pulley is fast on the driving-shaft and the other clutch member is 30 fast on another shaft placed end to end with the driving-shaft.

In carrying out my invention in the preferred way the pulley is made with a sufficiently wide rim to afford on one side of the 35 spokes or web an annular friction-surface on its inner side. Two nearly semicircular wooden segments are employed which are adapted to engage the inner side of the pulley-rim. At their opposite ends the segments 40 are joined by toggle-links of novel construction which are pivotally connected with radially-moving blocks carried by a supporting frame or driver keyed to the driving-shaft. These blocks are connected by links 45 to a ring or sleeve operated by a lever and mounted to slide in a direction parallel to the axis of the driving-shaft. The arrangement is such that when the blocks are moved outward to apply the segments to the pulley the 50 pivot-pins which connect the inner ends of the links to the ring are moved inward beyond the vertical plane of the pivots which connect the outer ends of the links with the

blocks, and thus the blocks are automatically locked in their outer position and the friction-segments are held securely in engagement with the pulley. 55

The toggles which connect the sliding blocks with the segments at one end of the driver are connected to the segments by non-adjustable shoes, while the shoes which connect the toggles at the opposite end of the driver to the segments are adjustable, so as to permit a proper operation of the mechanism and to compensate for wear. 60

The toggle-links are provided with shoulders so formed that when the sliding blocks are moved inward to withdraw the segments from the rim of the pulley said shoulders will engage each other and limit the pivotal movement of the toggles, and the toggles are formed with other shoulders which abut against the ends of the driver and also limit the movement of the toggles in such manner that a symmetrical movement of the segments on both sides of the driver is insured. 65

In the accompanying drawings, Figure 1 shows a side elevation of a band-pulley equipped with my improved friction-clutch, the clutch mechanism being shown in section 80 on the line 1 1 of Fig. 2. Fig. 2 shows a vertical central section on the line 2 2 of Fig. 1. Fig. 3 is a detail view, on an enlarged scale, partly in side elevation and partly in section, showing the adjustable connections between 85 the sliding block at one end of the driver and the adjacent ends of the friction-segments. Fig. 4 is a perspective view of the member of one of the adjustable shoes which is attached to the end of a friction-segment. Fig. 5 is a 90 perspective view of the adjustable member of the shoe. Fig. 6 is a bottom plan view of one of the fixed members of one of the adjustable shoes. Fig. 7 is a detail view illustrating the movement of the toggles and 95 showing how the inward movement thereof is limited or controlled in such manner as to provide for a symmetrical application of the friction-segments on opposite sides of the driver. Figs. 8 and 9 are perspective views 100 of the toggles which connect the shoes to the sliding blocks. Fig. 10 is a perspective view of one of the shoes which connects the toggles at one end of the driver with the friction-segments. 105

In the drawings I have shown my improve-

ments embodied in a clutch adapted to connect a loose pulley with a driver fast on the driving-shaft. It will be understood, however, that my improvements may be embodied in friction-clutches, friction-couplings, or other kinds. As shown, the pulley A is mounted loosely on the driving-shaft B. It has a rim *a* projecting from opposite sides of the spokes *b* and is preferably slightly wider on one side than on the other, and it is suitably finished to provide an annular friction-surface *a'* on the inner side of the wider portion of the rim. Babbitt metal *B'* is preferably interposed between the pulley-hub and the shaft, so that the shaft may revolve freely within the hub when the pulley is uncoupled. An oil-hole *B''*, closed by a screw-plug *b''*, is provided, as usual, for supplying a lubricant. It will thus be seen that the pulley is of usual or well-known construction. Substantially no change need be made in ordinary pulleys to apply my improved clutch, except that a suitable friction-surface *a'* is furnished. To the shaft B is rigidly secured a supporting frame or driver comprising a hub *c* and two radial arms C C'. The driver serves to support on the driving-shaft the friction-segments D D', which together form nearly a complete ring within the rim of the pulley. They are normally out of contact with the pulley-rim, but are adapted to bear against the friction-surface *a'* thereof when they are expanded. The segments may be made entirely of wood, but preferably they are backed by metal strips D², secured to the wooden segments by bolts *d*. Rods D³, projecting radially from opposite sides of the driver, connect with the segments midway between their opposite ends and serve to brace them and prevent sidewise movement thereof. These rods are rigidly attached to the driver, but are loosely connected with the segments for the purpose of allowing the segments to move inward to a slight extent when the clutch is uncoupled. These rods are shouldered, *d'*, to limit the inward movement of the segments. The sockets *d''*, into which the outer ends of the rods extend, have their opposite sides closed by vertical walls, so that the rods will hold the segments against sidewise movement.

Each arm of the driver is formed with a radial slot E, in which moves radially a block F, which is connected to the toggles at opposite ends of the segments and also to a ring or sleeve sliding on the hub of the driver. Each block F is formed with a middle portion *f*, which fits the opposite radial walls of the slot E, and it has flanges *f'*, which embrace the driver on opposite sides of the slot, and so serve to hold the block in place against sidewise movement, while allowing it to move freely in a radial direction. Each block F is formed with lugs *f''*, to which is jointed, by means of a pin *h*, a link H, the

opposite or inner end of which is jointed, by means of a pin *h'*, with a ring or sleeve I, mounted to slide on the hub *c* of the driver. The ring I is of usual construction and is operated by a lever J in the usual way; but the arrangement is such that when the ring I is moved inward to its full extent toward the driver it causes the pivot-pins *h'* to be moved beyond the vertical plane of the pins *h*, which connect the links H with the radially-sliding blocks, and in this way the blocks are automatically locked in their outermost position and cannot move out of this position until the ring I is positively moved outwardly on the hub *c* by the lever J.

It will be understood that when the segments are applied to the pulley pressure is applied endwise on the links H, so that they are held very firmly in the position to which they are adjusted. There is no liability of their shaking loose as the pulley rotates; but when the pivots *h'* are moved outward from the driver beyond the vertical plane in which the pivots *h* are located the clutch may readily be uncoupled.

The block F at one end of the driver is connected by toggle-links K with metal shoes L, rigidly attached to the adjacent ends of the segments. One of these shoes is shown in perspective in Fig. 10. As there shown and as also indicated in Figs. 1 and 2, each shoe L comprises a flanged plate *l*, secured to the end of a segment, and a bifurcated projection *l'*, which receives the outer end of a toggle-link K and to which the link is pivoted. The toggle-links K are of the form shown in Figs. 8 and 9 and are pivoted to the outer end of the adjacent block F in the manner shown in Figs. 1 and 2. It will be observed that the block F is formed with lugs *f³* *f⁴*, which receive between them the overlapping inner ends of the toggles, and a pin M, passing through the lugs and the toggles, serves to pivotally connect the toggles to the block.

The sliding block F at the opposite end of the driver is precisely the same in construction as that just described, and it is connected with the toggle-links K in the same manner, but the toggles are connected with the adjacent ends of the friction-segments by adjustable shoes in the manner presently described.

Before explaining this adjustable connection I will call attention to an important feature of construction shown in Figs. 3, 7, 8, and 9. It will be observed by reference to Fig. 7 that the outer ends of the slots E have diverging inclined surfaces *g* and that the toggles are formed with shoulders *k* *k'* *k''*. When the toggles are drawn inward by the blocks F, the shoulders *k* *k'* strike the ends of the driver on opposite sides of the slot E and the shoulders *k''* abut against each other. In this way the movement of the toggles is limited and a symmetrical application of the

segments is insured. If one of the toggles strikes the end of the driver before the other, it cannot move farther. Therefore the other toggle is given a further movement and is made to assume precisely the same position as the toggle first mentioned. When the shoulders k^2 come together, no further pivotal movement can be given to the toggles, and, as before stated, when the shoulders k' k^2 strike the ends of the driver a further inward movement of the toggles is prevented. The construction thus described is the same at opposite ends of the driver.

The adjustable shoes are clearly illustrated in Figs. 3 to 6 of the drawings, and they also appear in Figs. 1 and 2. Each shoe comprises two members N and O. The member N consists of a casting formed with a flat surface adapted to lie against the inner side of a segment at its end and a flange n , which overlaps the end of the segment. On its opposite side the casing is formed with a recess N' , provided with dovetailed grooves n' to receive the member O, and it has a downwardly-projecting flange or lug n^2 , which receives an adjusting-screw P. The member O (shown in Fig. 5) consists of a casting formed with dovetailed ribs o , adapted to enter the grooves n' , and a recess o' to receive the end of one of the toggles K. It also is formed with a portion o^2 , against which the set-screw P works. The member N is rigidly attached by bolts n^3 to the segment, while the member O is adjustable in the member N. By means of the set-screw P the member O may be so adjusted as to cause the pivot-pin m , that connects the toggle with the member O, to assume the desired position, and when adjusted to the desired position the member O may be locked against further movement by means of a set-screw Q. It will be understood that the adjustable shoes on opposite sides of one end of the driver are the same in construction and are adjusted in the same way, so that the pivots m can be made to assume the proper position to give the desired movement to the friction-segments. No adjustment of the links H is required, as all necessary adjustment is afforded by means of the adjustable shoes, whether it be to take up wear occurring on the wooden segments or to provide for a greater or less application of force to the segments. It will be understood that no matter what may be the adjustment of the shoes the toggles move inward to withdraw the segments always to the same extent and are always stopped in their inward movement in the manner illustrated in Fig. 7, so that the segments can never be withdrawn to such an extent as to unduly bend them or move them out of proper position. The adjustment of the shoes also governs the movement of the links H. By proper adjustment of the shoes

the links may be made to always move to the position shown in Fig. 2 when applying the clutch in such manner as to be self-locking, as before explained.

I claim as my invention—

1. In a friction clutch or coupling, comprising a driving and a driven part one of which is provided with two expansible segments, the combination of a supporting frame or driver to which the segments are connected at one end, toggles interposed between the opposite ends of the segments, a radially-moving block to which the toggles are pivotally connected, shoes rigidly attached to the adjacent ends of the segments and having members independently adjustable toward and from each other and to which the toggles are pivotally connected, a ring or sleeve movable in a line parallel with the axis of the driving-shaft, a link pivotally connected with the sliding block and a pivot connecting the inner end of the link with the ring or sleeve the axis of which is free to swing inward beyond the vertical plane of the pivot which connects the link with the sliding block whereby the parts are locked, substantially as specified.

2. The combination of the friction-segments, a driver connected at one end with the segments, a radially-sliding block carried by the opposite end of the driver, toggles pivotally connected with said block and shoes rigidly attached to the adjacent ends of the segments and having members independently adjustable toward and from each other and which are pivotally connected with the toggles.

3. In a friction clutch or coupling, the combination of friction-segments, a driver, a radially-moving block carried by the driver, a toggle pivotally connected with the block, a shoe member rigidly attached to one end of a segment, an adjustable member mounted to slide in the other member of the shoe, an adjusting-screw carried by the first-mentioned member of the shoe and engaging the adjustable member, and a locking-screw carried by the stationary member of the shoe and engaging the movable member thereof.

4. In a friction clutch or coupling, the combination of friction-segments, a driver, a radially-sliding block carried thereby and toggles pivotally connected with the adjacent ends of the segments and with the radially-sliding block which are shouldered on their upper sides to limit their movement inward toward the axis of the driving-shaft.

5. In a friction clutch or coupling, the combination of friction-segments, a driver, a radially-sliding block carried thereby, and toggles connecting the block with adjacent ends of the segments, said toggles being provided with shoulders which abut against each other when the segments are being withdrawn or uncoupled, and other shoulders

which strike the adjacent end of the driver to limit the inward movement of the toggles, substantially as specified.

6. A friction clutch or coupling, comprising friction-segments, a driver, a radially-sliding block carried thereby, adjustable shoes on adjacent ends of the segments and toggles connecting the adjustable shoes with the radially-sliding block, said toggles being formed with shoulders which abut against each other as the sliding block moves radially inward and with other shoulders which strike the adjacent end of the driver for the purpose specified.

7. The combination of friction-segments having radial sockets intermediate their ends,

a driver, radially-sliding blocks carried thereby, toggle connections between the sliding blocks and the ends of the segments and brace-rods for preventing sidewise movement of the segments projecting radially from opposite sides of the driver and which extend into the sockets in the middle portions of the segments, the opposite sides of said sockets being closed by vertical walls, for the purpose specified.

In testimony whereof I have hereunto subscribed my name.

PHILIP MEDART.
